UNITED STATES PATENT OFFICE.

CHARLES R. R. BECK, OF BALTIMORE, MARYLAND.

DRUGGIST'S STILL.

SPECIFICATION forming part of Letters Patent No. 509,282, dated November 21, 1893.

Application filed June 3, 1893. Serial No. 476,496. (No model.)

To all whom it may concern:

Be it known that I, CHARLES R. R. BECK, of Baltimore city, in the State of Maryland, have invented a new and useful Improvement 5 in Druggists' Stills, of which the following is a specification.

My invention is an improvement in what are known as pharmaceutical or druggists' stills used by pharmacists or druggists in 10 distilling the various extracts and waters in the course of business and the invention seeks to provide improvements in the still whereby the condensations will all be collected and conducted out of the still instead 15 of permitting some of the condensations to fall back into the heating vessel and the invention consists in the special constructions and combinations of parts as will be herein-after described and pointed out in the claims. 20 In the drawings—Figure 1 is a side view and Fig. 2 a vertical section of a still embodying my improvement.

In the construction shown I employ the water tank A, the vessel B and the condensing hood C, said parts having projecting flanges which lap each other and are firmly secured together. The joint may be packed 25 by a rubber gasket or in other suitable manner and screw fastenings may be employed to 30 clamp the several flanges together as shown.

The tank A in practice contains water and the vessel B fits in said tank and has at its top a flange resting upon the top flange of the tank. This vessel B contains water or 35 the other material it is desired to distill and heat is applied to the tank A, it may be by placing said tank upon a stove or other heater. An outlet is provided near the top of the tank A for steam and the overflow 40 from said tank. The fumes from the contents of the vessel rise and are condensed against the interior of the condensing cover or hood. This hood is cooled by water being preferably water jacketed and having an inlet 1 and an outlet 2 to permit the circulation 45 of cooling water from a suitable supply such water circulating between the inner and outer shells 3 and 4 of the condenser hood. This hood is preferably made conical 50 and has at its apex an opening 5 closed by a

suitable valve 6 through which the vessel B may be filled and replenished.

At the base of the condenser I provide a trough D which collects the condensations which accumulate and flow down the hood, 55 and an outlet pipe is provided at d leading from the trough D and serving to conduct off the distillations.

It is found in practice that the condensations near the top of the hood will form in 60 such quantities that they will accumulate and drop back into the vessel B before reaching the trough D thus reducing the capacity of the still by requiring redistillation and a collection of the distillations from only a 65 part of its condensing surface. To avoid this difficulty I provide an intermediate collecting trough E arranged between the trough D and the crown of the hood and adapted to collect the condensations before they accumulate in such quantities as to drip back into the vessel. This trough E has an outlet e which 70 preferably communicates with the outlet d so that the distillations from both troughs D and E may be discharged into the same 75 vessel. This outlet pipe e it will be seen is arranged within the water jacket and is cooled thereby so that there will be no danger of vaporizing the distillations after they reach the said pipe e. This arrangement of the 80 pipe e within the water jacket also avoids any diminution of the condensing surface as will be readily understood from Fig. 2.

Having thus described my invention, what I claim as new, and desire to secure by Letters 85 Patent, is—

1. In a still substantially as described the improved condensing hood made conical provided at its apex with a filling opening and having from base to top a surrounding water 90 jacket provided near its top and bottom with inlet and outlet openings whereby to permit circulation of water through said jacket, a base trough arranged within the hood and a supplemental trough in said hood above the 95 base trough and provided with an outlet or discharge pipe substantially as set forth.

2. An improved still consisting of the tank, the vessel fitted therein, said parts having projecting lapping flanges at their upper 100

ends, the hood having its lower end rested upon and clamped to said flanges provided at its apex with a filling opening and having the water jacket inclosing it and provided with a water inlet and exit whereby water may be circulated through the jacket, a base collecting trough arranged in said hood and a supplemental trough arranged in the hood

above the base trough and having an outlet pipe all substantially as and for the purposes so set forth.

CHARLES R. R. BECK.
